(57) **CLAIM**

The ornamental design for a magnetic block, as shown and described.

DESCRIPTION

FIG. 1 is a front perspective view of a first part of a magnetic block, shown separately for the clarity of illustration;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view of a second part of a magnetic block, shown separately for the clarity of illustration;

FIG. 10 is a bottom perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof;

FIG. 16 is a bottom view thereof;

FIG. 17 is a front perspective view of a third part of a magnetic block, shown separately for the clarity of illustration;

FIG. 18 is a bottom perspective view thereof;

FIG. 19 is a front view thereof;

FIG. 20 is a rear view thereof;

FIG. 21 is a left side view thereof;

FIG. 22 is a right side view thereof;

FIG. 23 is a top view thereof;

FIG. 24 is a bottom view thereof;

FIG. 25 is a front perspective view of a fourth part of a magnetic block shown separately for the clarity of illustration;

FIG. 26 is a bottom perspective view thereof;

FIG. 27 is a front view thereof;

FIG. 28 is a rear view thereof;

FIG. 29 is a left side view thereof;

FIG. 30 is a right side view thereof;

FIG. 31 is a top view thereof;

FIG. 32 is a bottom view thereof;

FIG. 33 is an exploded perspective view of the magnetic block showing my new design; and,

FIG. 34 is an assembled perspective view thereof.

The broken lines in the drawings illustrate the portions of the magnetic block, which form no part of the claimed design.

1 Claim, 34 Drawing Sheets
